GAS AND OIL SEPARATOR

Jose Guadalupe Mejia Lopez, Mexico, D. F.,
MexicoApplication November 16, 1938, Serial No. 239,892
In Mexico May 14, 1938

4 Claims. (Cl. 183—2.7)

This invention relates to an improved gas and oil separator and more particularly to a separator which is adapted to be connected directly to a well casing.

5 An object of this invention is to provide an improved separating device which may be connected to a well casing and which will reduce the normal pressure of the gas or oil as it is discharged from the well casing in addition to separating the liquids from the vapors.

10 Another object of this invention is to provide an improved check valve in combination with a perforated partition in a separator which is operated by means of a float so as to control the passage of liquids and gases through the refining system which is adapted to be connected to this separator.

15 A further object of this invention is to provide an improved check valve which is operated by gravity to open the valve and which is operated by means of a float in order to close the valve.

20 Embodying the objects aforesaid and others which may hereinafter appear, the invention consists of the novel construction, combination 25 and arrangement of parts as will be more specifically referred to and illustrated in the accompanying drawing wherein an embodiment of the invention is shown, but it is to be understood that changes, variations and modifications may 30 be resorted to which fall within the scope of the invention as claimed.

In the drawing:

Figure 1 is a vertical section through a separating tower constructed according to an embodiment of this invention.

Figure 2 is a sectional view taken on the line 2—2 of Figure 1.

Figure 3 is a sectional view taken on the line 3—3 of Figure 1.

40 Figure 4 is a sectional view taken on the line 4—4 of Figure 1, and

Figure 5 is a sectional view taken on the line 5—5 of Figure 1.

45 Referring to the drawing, the numeral 10 designates generally an upstanding hollow structure or separating tower comprising a cylindrical body 11, a top wall 13 and a wall 12. The latter is positioned within and arranged upwardly from the lower end of the body 11. The top wall 13 is provided with a marginal flange 14 extending over the upper end of the cylindrical body 11 and this flange may be secured to the body 11 by welding, rivets or other fastening means. The bottom wall 12 is of concave construction and 50 is preferably welded, riveted or otherwise fastened

to the inner face of and above the lower end of the body 11.

A fluid intake pipe 15 is extended axially through the top wall 13 and one end of the pipe 15 is adapted to be connected to a suitable source 5 of fluid supply similar to the separator tank member in my co-pending application, Serial No. 239,890, filed Nov. 10, 1938, for a Refining process. The pipe 15 is extended vertically through the receptacle or body 11 to a point below the vertical center thereof and is extended through a perforated partition plate 16 having a plurality of holes 17 therethrough. The pipe 15 is sealed in the top wall 13 by means of nuts 18 and 19 and also suitable gaskets 20 and 21. The lower end of the pipe 15 is open and discharges into a receiving chamber 22 for a body of gas and oil and such chamber is positioned in the lower portion of the body 11. The perforated partition 15 16 divides the structure or tower 10 into the lower 20 chamber 22 aforesaid and an upper separated gas or vapor receiving or collecting chamber 23. The perforated plate 16 has the peripheral edges thereof secured as by welding or the like to the inner surface of the body 11 and the outer portion 25 of the plate 16 which surrounds the perforated portion of the plate 16 is imperforate as at 24. The imperforate portion 24 is provided on the under side thereof with a depending valve seat 25 provided in the form of a V-shaped annular 30 rib. An axially apertured disc-like valve 26 having a gasket 27 on the upper side thereof is adapted to engage the valve seat or rib 25. The valve 26 is provided with a flanged marginal portion 28 which acts to keep the gasket 27 from lateral 35 movement.

The perforated portion of the plate 16 provides an intake for the upper chamber 23 for the separated gases or vapors which pass upwardly from off of the body of gas and oil received in 40 the chamber 22. The valve 26 is for the purpose of controlling such intake.

The valve 26 has a central opening 29 in which the pipe 15 is loosely received so that the valve 26 may slidingly engage the pipe 15. Preferably, 45 the pipe 15 is provided with a pair of opposed ribs or keys 30, and the valve 26 is provided with opposed key-ways 31 so that the valve 26 will be held against rotation relative to the pipe 15 although the valve 26 may move vertically along 50 the pipe 15.

The valve 26 is secured to a cylindrical hub or bushing 32 which loosely engages the pipe 15 and extends downwardly therefrom. The bushing 32 is also provided with a key-way 33 to re- 55

ceive the key 30 carried by the pipe 15. An annular float member 34 is secured to a U-shaped supporting member 35 which is also secured to the bushing 32. The float 34 extends downwardly from the bushing 32 and is adapted to rest on a plate 36 which is secured about the pipe 15 by means of a nut 37. The nut 37 may be adjusted vertically along the pipe 15 so as to regulate the opening of the valve 26.

10 The tower 10 is provided in the lower portion thereof with a sediment outlet pipe 38 which is secured to the central point of the bottom wall 12, and is extended through the wall of the cylindrical member 11 and connected to a suitable receptacle similar to that disclosed in my aforesaid application on a refining process filed of even date herewith. The pipe 38 is firmly secured to the tower 10 by means of nuts 39 and 40 engaging on opposite sides of the cylindrical wall 11. A heavy liquid outlet pipe 41 provided with a depending portion 42 within the tank 11 is extended through the wall of the tank 11 adjacent the lower portion thereof and secured by means of nuts 43 and 44. The pipe 41 may be connected to a suitable heavy component receptacle similar to that shown in my aforesaid application on a refining process. The vapors or gases which rise in the vapor chamber 23 are drawn off therefrom by means of a pipe 45 which is secured to the tower 10 by means of nuts 46 and 47. The pipe 45 is adapted to be connected to a condensing tower similar to that disclosed in my aforesaid application on condensing towers filed of even date herewith.

15 20 25 30 35 40 45 50 55 60 65 70 75

35 In the use of this separator, the incoming fluid will pass downwardly through the pipe 15 and be first discharged to the lower or liquid chamber 22. Normally, the valve 26 will be in open position by reason of the weight of the valve 26 and the component parts thereof so that the gases or vapors may rise upwardly through the perforated plate 16 and pass out through the outlet 46. In the event the fluid in the chamber 22 rises too high, the float 34 will move the valve 45 26 to a closed position.

The heavier oil or liquids in the liquid chamber 22 are drawn off through either or both pipe connections 38 and 41. Where there is not a great deal of sediment in the fluid, the pipe 38 may be used with the pipe 41 to remove the liquids from the liquid chamber 22. However, where a considerable amount of sediment is in the fluid, the pipe 38 may be connected to a suitable refuse receptacle and the oil removed through the pipe 41. It will, of course, be understood that the hereinbefore described separator may be either connected directly to a well casing, particularly a gas well casing or may be connected to an oil casing or a stock tank from which the oil is pumped and discharged into the separator 10 through the pipe 15.

What I claim is:

1. In a gas and oil separator, an upstanding hollow structure formed of a cylindrical body, a top wall and a bottom wall, a partition within and secured to the inner face of said body and dividing said structure into an upper chamber for receiving separated gas and a lower chamber for receiving combined gas and oil, said partition having a perforated portion constituting an intake to the upper chamber for the separated gas and an imperforated portion surrounding said perforated portion, an annular valve seat depending from said imperforated portion and bordering said perforated portion, a combined gas

and oil delivering pipe suspended from said top wall, extending through said upper chamber, disposed axially of said perforated portion, depending from said partition and discharging into the upper part of said lower chamber, a float 5 operated controlling valve structure for said perforated portion for coaction with said valve seat mounted about, slidably connected to and suspended by, said pipe below and in normal spaced relation with respect to said seat, a take-off pipe for said separated gas receiving chamber, and a pair of take-off elements for and communicating with said lower chamber, one being arranged above and the other below said bottom wall.

2. In a gas and oil separator, an upstanding hollow structure formed of a cylindrical body, a top wall and a bottom wall, a partition within and secured to the inner face of said body and dividing said structure into an upper chamber for receiving separated gas and a lower chamber for receiving combined gas and oil, said partition having a perforated portion constituting an intake to the upper chamber for the separated gas and an imperforated portion surrounding said perforated portion, an annular valve seat depending from said imperforated portion and bordering said perforated portion, a combined gas and oil delivering pipe suspended from said top wall, extending through said upper chamber, disposed axially of said perforated portion, depending from said partition and discharging into the upper part of said lower chamber, a float 10 operated controlling valve structure for said perforated portion for coaction with said valve seat mounted about, slidably connected to and suspended by, said pipe below and in normal spaced relation with respect to said seat, a take-off pipe for said separated gas receiving chamber, and a pair of take-off elements for and communicating with said lower chamber, one being arranged above and the other below said bottom wall.

15 20 25 30 35 40 45 50 55 60 65 70 75

3. In a gas and oil separator an upstanding cylindrical body, top and bottom walls carried by said body, a partition secured to the inner face of the body and dividing the body into an upper chamber for receiving gas and a lower chamber 55 for receiving combined gas and oil, said partition having a perforated portion constituting an intake to the upper chamber, and an imperforated portion surrounding said perforated portion, an annular valve seat about said perforated portion 60 and depending from said partition, a combined gas and oil delivery pipe extending axially through said top wall and terminating below said partition, opposed keys carried by said pipe below said partition, a disc-shaped valve member 65 loose on said pipe and formed with opposed keyways to receive said keys, an upstanding flange carried by said valve member, a disc-shaped gasket seated on said valve member within said flange, a bushing fixed to said valve member and 70 slidingly engaging said pipe, a float about said pipe, a U-shaped support carried by said bushing and fixed to said float, and an annular float limiting plate adjustably carried by said pipe.

4. In a gas and oil separator an upstanding 75

cylindrical body, top and bottom walls carried by said body, a partition secured to the inner face of the body and dividing the body into an upper chamber for receiving gas and a lower chamber for receiving combined gas and oil, said partition having a perforated portion constituting an intake to the upper chamber, and an imperforated portion surrounding said perforated portion, an annular valve seat about said perforated portion and depending from said partition, a combined gas and oil delivery pipe extending axially through said top wall and terminating below said partition, opposed keys carried by said pipe below said partition, a disc-shaped valve member loose on said pipe and formed with opposed keyways to receive said keys, an up- standing flange carried by said valve member, a disc-shaped gasket seated on said valve member within said flange, a bushing fixed to said valve member and slidably engaging said pipe, a float about said pipe, a U-shaped support carried by said bushing and fixed to said float, an annular float limiting plate adjustably carried by said pipe, a draw-off pipe connected to said bottom wall, a liquid outlet pipe extending through said cylindrical body adjacent said bottom wall and including a depending extension confronting said bottom wall, and a gas outlet pipe connected to said cylindrical body and communicating with said upper chamber adjacent said top wall.
